US00D611860S

(12) **United States Design Patent**
Gismervik

(10) **Patent No.:** **US D611,860 S**
(45) **Date of Patent:** **** Mar. 16, 2010**

(54) **LEVEL SENSOR**

(75) Inventor: **Øystein Gismervik**, Fyllingsdal (NO)

(73) Assignee: **Wema-System AS**, Laksevag (NO)

(**) Term: **14 Years**

(21) Appl. No.: **29/335,756**

(22) Filed: **Apr. 21, 2009**

(51) **LOC (9) Cl.** **10-04**

(52) **U.S. Cl.** **D10/101**

(58) **Field of Classification Search** **D10/101;**
73/1.73, 149, 290 V, 290 R, 293, 304 R, 304 C,
73/305, 313, 314, 317, 865.9
